ARTHUR O. AUSTIN, OF NEAR BARBERTON, OHIO, ASSIGNOR, BY MESNE ASSIGNMENTS, TO THE OHIO BRASS COMPANY, OF MANSFIELD, OHIO, A CORPORATION OF NEW JERSEY

POLE FITTING

Application filed May 16, 1930. Serial No. 453,064.

This invention relates to fittings for the attachment of guy wires to wood poles, and has for one of its objects the provision of a fitting which can be adapted to poles of different sizes, which will be simple and economical to manufacture and install, and which will not injure the pole nor interfere with the electrostatic field nor direct electrical discharges toward the center of the pole.

10 Other objects and advantages will appear from the following description.

The invention is exemplified in the combination and arrangement of parts shown in the accompanying drawing and described in 15 the following specification, and it is more particularly pointed out in the appended claims.

In the drawing:

Fig. 1 is a plan of a fitting showing one 20 embodiment of the present invention.

Fig. 2 is an elevation of the fitting shown in Fig. 1.

Fig. 3 is a fragmentary plan of a modified 25 form of the invention.

Wood supports are frequently used for holding up the insulators of power conductors. In order to prevent interruptions 30 due to flashover, of the service supplied by the power conductor, particularly under lightning conditions, it is frequently advisable to make use of the resistance of the wood to flash over under high voltages. It is frequently possible to develop an even higher flashover in the wood than in an insulator

35 where the wood is used efficiently in combination with the insulator. It is comparatively easy to develop this high insulation on a normal structure where metal parts tending to cut out the insulation of the pole are not necessary. On guyed structures, 40 however, the metallic guy running to ground eliminates a large part of the insulation and there is a tendency for the remaining part to be shattered by heavy electrical discharges produced by lightning. In most cases, the 45 damage is greatly aggravated where any conductor member penetrates the pole. Because of electrostatic influence, there is a tendency for a discharge caused by lightning to take the center of the pole or wood member.

Therefore, if a discharge is once started in the center of the pole, it may cause serious shattering. In order that this discharge may be kept away from the center of the pole, it is advisable to keep attachments on 55 the outside, using as few projecting or entering points as possible. For attaching guy insulators, it is possible to use a cable or wrapping around the pole which, although it eliminates penetrating members in so far 60 as the cable is concerned, generally requires the use of lag bolts or other means for holding the cable up.

Where ordinary split bands formed of 65 straps are clamped to a pole and a guy or strain insulator is attached to the ears of the band on one side of the pole, there is a tendency for the band to pull down on this side, making it necessary to use lag bolts or other supports for taking the vertical load. The 70 penetration of these lag bolts or spikes tends to form a point of entry for any severe electrical discharge traversing the pole.

With the improved type of fitting comprised in the present invention, the load is applied approximately at diametrically opposite points in a clamped band, so that the vertical component will be almost equally distributed around the pole. This makes it comparatively easy to maintain the position 75 of the clamp. Any slipping which is due to unequal loading on the side is also avoided. With this scheme it is possible to attach a strain insulator in a preferred location so that a high effective flashover will be developed even for the guyed structure. It is highly desirable to keep the effective capacitance of the fittings small so that over-stress 80 will not develop, thereby lowering the effective flashover voltage. Owing to the variation in pole diameters, a fitting must be provided which will have considerable range 85 of adjustment. It is also desirable to provide a fitting which will distribute the load over the pole so that damage to the outer fibers under the bearing area will be avoided. It is also highly desirable to produce a reliable fitting and one at low cost. The type of fitting shown in the drawing makes it possible 90 to hold the strain insulator in a definite position.

100

tion, and is relatively low in cost and easily installed.

In the form of the invention shown in Fig. 1, arcuate clamping members or straps 10 are formed into the shape illustrated by pressing or other suitable manufacturing processes. The members are relatively thin and therefore can be made to conform to the pole readily, and, at the same time, provide a wide bearing area between the band and the pole. Sockets or bosses 11 are provided with suitable holes for the tightening bolts 12. These bolts may have a long threaded portion permitting of a material take-up to accommodate various sizes of poles or, if desired, different lengths of bolts may be used, or bolts having a nut on each end. With this type of construction, there is a certain amount of resiliency in the bands so that they will have a tendency to stay tight even though the pole changes its diameter under changes in atmospheric conditions. In general, it is preferable to provide extensions 13 beyond the sockets 11 at the ends of the straps. These extensions may be made long if desired so that the tendency for the band to bend at the socket will be reduced. If desired, the ends 13 may be made to overlap. In general these ends are curved slightly outwardly so that there will be no tendency to dig into the fibre in clamping up. In order that the vertical component of the force on the band may be distributed, the attachment is made through two bosses 15, substantially diametrically opposite each other, through which the link 16 passes.

In the form shown in Fig. 3, bolts 20 are located in sockets 21 and form trunions for the link 22. This latter arrangement gives a wide range of vertical movement for the attachment link or yoke 22. If desired, the bands 10 may be provided with a number of small teeth 23 which grip the pole but, at the same time, do not project into the pole any great distance. Where these are located well toward the center of the band, they will be more or less screened electrically by the remaining portion. The teeth may be made by punching sections in the band or by welding on small points. If desired, the bolt member 20 may be given a point 24 which will be drawn into the pole for gripping.

I claim:

1. A fitting for attaching a guy to a pole comprising a band for gripping the pole, said band being split at approximately diametrically opposite positions on said pole, said positions lying approximately in the vertical plane of the guy, the guy having branch portions attached to the respective portions of said band at opposite portions of said pole and in a vertical plane at an angle to the vertical plane of said guy.

2. A fitting for attaching a guy to a pole comprising a pair of arcuate clamping mem-

bers, means for drawing said clamping members together about a pole, and attachments for a guy at approximately the mid portions of said clamping members and a single guy having branches secured respectively one to each of said attachments.

3. A fitting for attaching a guy to a pole comprising a pair of arcuate clamping members having radially projecting attachment lugs between the ends of said members, a guy having branches secured respectively one to each of said lugs and means adjacent the ends of said arcuate members for clamping said members about a pole.

4. A fitting for a wood pole comprising a metal strap having a hollow lug pressed outwardly therefrom between the ends thereof, said lug being perforated, and an attachment bolt extending through the perforation of said lug.

5. A fitting for securing a guy to a wood pole comprising a pair of metal straps, each having a lug pressed outwardly at the mid portion thereof, and an attachment yoke having the ends thereof secured to said lugs respectively at opposite sides of the pole.

6. A fitting for attaching a guy to a wood pole comprising a pair of arcuate straps having lugs at their mid portions, adjustable means for drawing the ends of said straps together to clamp said fitting about a pole, and a yoke having the ends thereof secured to said lugs.

7. A fitting for a wood pole comprising a pair of arcuate straps having lugs projecting radially from the mid portions thereof respectively, means for clamping said straps to a wood pole, and an attachment yoke having the ends thereof projecting through said lugs in a direction transverse to the axis of the pole.

8. A fitting for securing a guy to a wood pole comprising a pair of arcuate straps having lugs projecting radially from the mid portions thereof respectively, means for clamping said straps about a pole, trunnions projecting radially from said lugs, and a yoke pivotally mounted on said trunnions.

9. A fitting for attaching a guy to a pole comprising an arcuate strap having a lug projecting outwardly therefrom, a trunnion secured to said lug and having a pointed end for penetrating the surfaces of the pole to prevent said strap from slipping.

10. An attachment fitting comprising curved straps, a yoke means for attaching opposite ends of said yoke to the mid portions of said straps respectively, and threaded means for connecting the ends of said straps and for drawing said straps tightly about an enclosed member.

11. An attachment fitting comprising a pair of arcuate straps having lugs pressed outwardly therefrom at their mid portions respectively, a yoke having its ends secured

to said lugs, outwardly extending lugs formed on said straps adjacent the respective ends thereof, and a threaded bolt extending through said last named lugs for drawing the ends of said straps together to clamp said straps upon an enclosed member.

12. An attachment fitting comprising a pair of curved straps, means for attaching a yoke to the central portions of said straps respectively, and means for drawing the ends of said straps together to clamp said straps about an enclosed member, the ends of said straps being inclined outwardly to prevent said ends from entering the surface of said member as they are drawn together.

In testimony whereof I have signed my name to this specification this 14th day of May, A. D. 1930.

ARTHUR O. AUSTIN.
